UNITED STATES PATENT OFFICE.

FRANK R. McBERTY, OF EVANSTON, ILLINOIS, ASSIGNOR TO WESTERN ELECTRIC COMPANY, OF CHICAGO, ILLINOIS, A CORPORATION OF ILLINOIS.

INCLOSING CASE FOR TELEPHONE SETS.

No. 822,464.

Specification of Letters Patent.

Patented June 5, 1906.

Application filed December 10, 1904. Serial No. 236,400.

To all whom it may concern:

Be it known that I, FRANK R. McBERTY, a citizen of the United States, residing at Evanston, in the county of Cook and State of Illinois, have invented a certain new and useful Improvement in Inclosing Cases for Telephone Sets, of which the following is a full, clear, concise, and exact description.

My invention relates to a telephone set, and has for its object to provide an improved construction for the containing-case thereof, whereby the telephone of the set may be conveniently carried within the case when not in use and access easily and quickly had thereto when desired.

I will describe my invention more particularly by reference to the accompanying drawings, wherein—

Figure 1 is a view in front elevation of a portable telephone set equipped in accordance with my invention with the front cover thereof removed and the door opened to permit access to the telephone instrument. Fig. 2 is a perspective view of the same. Fig. 3 is a detail sectional view of the pocket with the door closed; and Fig. 4 is a similar view, but with the door opened, showing the means for ejecting the instrument and the means for limiting the outward movement of the door.

The same parts are indicated by similar letters of reference on each of the several figures of the drawings.

The telephone set illustrated, which is of the portable type, is provided with a containing-case *a* having a shelf *b*, upon and above which is mounted the usual telephone apparatus, which may comprise a generator, induction - coil, condenser, batteries, and other parts, as shown.

The telephone set is provided in accordance with my invention with a pocket below the shelf *b*, and having a door *c* hinged to the base of the case and carrying upon its inner surface a cradle *d*, preferably of sheet metal, which surrounds the head telephone instrument *T* as it lies in the pocket and serves to eject or draw it out from the pocket when the door is opened, the cradle *d* retaining the instrument in an accessible position on the open door as a shelf or support. The telephone instrument may comprise a transmitter and receiver mounted upon opposite ends of a handle, as shown.

The cradle *d* is provided with a curved lip *d'*, which when the door is closed is engaged by a leaf-spring *d²* within the case, as shown in Fig. 3, said spring thus serving as a catch to prevent the door from being accidentally opened.

A stop *e* is provided for limiting the outward swing or movement of the door and serves to retain the door in a position to support the telephone instrument. This stop may be mounted upon the inner face of one side of the containing-case in position to be engaged by the lip *d'* when the door is opened outwardly a given distance, as shown in Fig. 4. A handle *f* is also provided for the door, whereby the lip *d'* of the cradle may be disengaged from the spring-catch *d²* and the door swung open to permit access to the telephone instrument.

By virtue of the construction above described the telephone set is made very compact, and the telephone instrument concealed and protected when not in use, and at the same time ready and convenient means is obtained for depositing and withdrawing the instrument when desired. It is evident that my invention may be conveniently employed in telephone sets other than those of the portable type herein illustrated.

I claim—

1. The combination with a telephone set, of a containing-case therefor, a hinged door for said case, a trough mounted upon the inner surface of said door and carrying the telephone of the set, a lip for said trough, and a spring adapted when the door is closed to engage said lip to hold the door in such position.

2. The combination with a telephone set, of a containing-case therefor, a door hinged to the base of the case and adapted to be swung outwardly, a trough mounted upon the inner surface of the door and carrying the telephone of the set, a lip for said trough, a spring adapted when the door is closed to engage said lip to hold the door in such position, and a stop carried by the case adapted to engage said lip when the door is opened to limit the outward movement of said door.

3. The combination with a telephone set, of a containing-case therefor, a door hinged to the base of the case and adapted to be swung outwardly, a cradle mounted upon the inner surface of the door and adapted to eject

the telephone of the set, a lip for said cradle, a spring adapted when the door is closed to engage said lip to hold the door in such position, a handle for said door whereby the lip 5 may be disengaged from said spring and the door opened, and a stop carried by the case adapted to limit the outward movement of said door.

4. The cradle adapted to hold the telephone and transmitter and consisting of the door combined with the sheet-metal trough mounted on the inner surface of the door, said trough having a curved lip combined

with a spring-catch adapted to engage the same when the door is closed, and a stop 15 adapted to engage said trough when the door is swung open to limit the movement thereof, the engagement of the catch being overcome when power is applied to open the door.

In witness whereof I hereunto subscribe 20 my name this 29th day of October, A. D. 1904.

FRANK R. McBERTY.
